UNITED STATES PATENT OFFICE.

GEORGE L. STREBLER, OF ST. LOUIS, MISSOURI.

INTERNAL-COMBUSTION MOTOR.

1,314,716.

Specification of Letters Patent.

Patented Sept. 2, 1919.

Application filed November 12, 1917. Serial No. 201,485.

To all whom it may concern:

Be it known that I, GEORGE L. STREBLER, a citizen of the United States, residing in the city of St. Louis and State of Missouri, have invented certain new and useful Improvements in Internal-Combustion Motors, of which the following is a specification.

My invention relates to internal combustion motors, and consists in the combinations, construction and arrangements hereinafter described and claimed.

The objects of my invention are, first, to provide a motor having a vertically reciprocating compression sleeve provided with an explosion head near its lower end and adapted to operate in conjunction with a stationary compressing block having a longitudinal explosion chamber leading from overhead gas-intake and exhaust valves to and communication with an expansion chamber formed within the compression-sleeve and with a compression sleeve bearing; second, to provide means for continuously lubricating the wall of the stationary compression block and the wall of the reciprocating compression sleeve; and, third, to provide a comparatively short connecting rod for connecting the crank-shaft with the reciprocating compression-sleeve.

Other objects and advantages will appear in the following specification, and the novel features of my improvements will be clearly pointed out in the claim hereto appended.

My invention is clearly illustrated in the accompanying drawings forming a part of this application, on which, similar characters of reference denote similar parts throughout the several views.

Referring to the drawings:

Figure 1, is a vertical sectional view of an internal combustion motor, with parts thereof broken away, and constructed in accordance with my invention.

Fig. 2, is a detail partly in section, clearly illustrating the stationary compression-block, the reciprocating compression-sleeve, the compression-sleeve bearing, and the self, continuous lubricating means.

Fig. 3, is a vertical sectional view of the upper parts of the motor.

Fig. 4, is a transverse sectional view of 55 the motor taken on line A—A of Fig. 3.

Fig. 5, is a detail showing modified means for supporting the stationary compression-block and protecting the inner working parts.

Referring to the drawings the reference character 1 designates the lower half of a crank-case, while 2 designates the upper half of the crank-case. The two halves are united by means of suitable fastening means 3 and the upper wall of the upper half 2, of the crank case, is provided with a suitable opening 4.

A suitable crank shaft 5 is supported within the crank-case by means of suitable 70 bearings 6. Mounted upon the crank-shaft 5 in the usual manner is a comparatively short connecting-rod 7.

The crank-case is adapted to be sealed from all sides so that it may be filled with 75 lubricant for lubricating by means of full splash or floating system. In fact the crank-case is filled with lubricant to the height of line B—B, as shown, in Fig. 1, thereby providing a body of oil for the crank shaft to 80 turn in.

Mounted upon the upper face of the upper half of the crank-case 2 is a cylindrical element designated 8. This element 8 is secured thereto by means of suitable fastening 85 means.

The lower portion of the cylindrical element 8 which will be known as a compression sleeve bearing 9 is provided with a ground, smooth inner wall 10 arranged concentric with the opening 4 of the crank-case. The upper edge of the inner wall 10 is beveled or terminates in an outwardly and upwardly inclined wall 11 forming an annular lubricant reservoir 12 surrounding 95 a compression-sleeve to be described herein-after.

The upper portion of the cylindrical element 8 is cored so as to form a water chamber 13 adapted to surround the upper parts 100 of the motor. A suitable water inlet 14 and a water outlet 15 is provided, as shown in Fig. 3. The upper part of the cylindrical element 8 is provided with an annular

shoulder 16 for supporting a compression-block hereinafter fully described.

A reciprocating compression-sleeve 17 having a ground outer surface 18 and a ground inner surface 19 is slidably mounted within the compression sleeve bearing 9 formed at the lower portion of the cylindrical element 8, as clearly shown in Fig. 1. The compression-sleeve 17 is provided near its lower end with an explosion-head 20. The lower end of the compression-sleeve 17 is connected by means of a wrist-pin 21 with the upper end of the connecting rod 7 which is adapted to impart a reciprocating movement to the compression sleeve 17. The upper end of the compression-sleeve 17 is open and is provided with a beveled upper inner edge 22 forming an annular lubricant reservoir 23, around a compression-block, 20 which will now be fully described for continuously lubricating the outer surface thereof.

A stationary compression-block 24 is employed having the ground outer surface 25 and provided near its lower end with suitable piston rings 26. The compression-block 24 is adapted to tightly fit into or telescope the compression sleeve 17, as clearly shown in Fig. 1, thereby providing an expansion chamber 27 between the lower face of the compression block 24 and the upper face of the explosion-head 20 of the compression-sleeve 17.

The compression-block 24 is provided with a longitudinal explosion-chamber or channel 28 communicating at its lower end with the expansion chamber 27, and at its upper end with valves hereinafter described. A water chamber 30 is formed in the compression-block 24, and adapted to nearly surround the explosion-chamber 28 thereof. A cold water inlet duct or channel 31 is also formed in the compression-block thus permitting cold water to be fed directly to the bottom of the channel 31 and feed to the bottom of the water-chamber 30 through the opening or passage 32. A water inlet pipe 33 is connected at the upper end of the water inlet channel 31 and a water outlet pipe 34 is connected at the upper end of the water-chamber 30 to permit outward passages of water heated from explosions within the compression block 24.

The upper end of the compression-block 24 is provided with an annular flange 35 adapted to rest upon the annular shoulder 16 of the cylindrical element 8 for supporting the compression-block 24 in a fixed or stationary position. It will here be observed that the cylindrical element 8 acts as a support for the compression-block 24, as a cooling element for the upper parts of the motor and further as a sealing element to prevent foreign substances from collecting on the outer wall of the compression-sleeve 17

as well as the outer wall of the compression-block 24.

The outer surface of the compression block 24 is provided with a pair of helical oil grooves 36, as clearly shown in Fig. 2. 70

A threaded spark plug opening 37 is formed in the upper end or wall 38 of the explosion-chamber 28.

The valve housing 39 having open ends is formed at the upper end of the compression-block 24 and to one side of the explosion chamber 28, and a second valve-housing 40 having open ends is formed at the upper end of the compression-block 24 integral with housing 39 and is provided with an exhaust 80 port 41.

A valve-cage 42 is threaded into position within the valve housing 39. An inlet valve stem 43 having a valve head 44 is slidably supported by means of the valve cage 42 and held normally closed by means of a coiled spring 44. The passage of the housing 39 connects the inlet valve to an intake manifold 45.

A valve cage 46 having an exhaust port 47 90 adapted to register with exhaust port 41 is positioned within the passage of the valve-housing 40 and securely held in position by means of the threaded-nut 48. An exhaust valve stem 49 having a valve head 50 95 is slidably supported by means of the valve-cage 46 and held in a normally closed position by means of a coiled spring 51.

The means for actuating the exhaust valve comprises a rocker member 52 pivoted as at 100 53 to a support 54 and provided with the upper arm 55 and the lower arm 56. The upper end of the upper arm 55 is adapted to force the exhaust valve-stem 49 and head 50 inwardly, at timed intervals, to permit exhaust gases to escape from the explosion chamber 29 through the valve-cage 46 and port 41 into the exhaust manifold 57. The lower end of the lower-arm 56 is adapted to be forced outwardly, thereby moving the 110 upper end or arm 55 inwardly by means of a plunger 58 slidably mounted in a bushing 59, carried by the boss 60 of the upper half 2 of the crank case. The plunger 58 is in turn actuated by means of a suitable exhaust cam 115 61 fixed to the shaft 62, coming in contact with the roller head 63 of the plunger 58, as clearly shown in Fig. 1.

The inner surface of the upper half 2 of the crank-case is provided with offset portion or lip 64 above the roller-head 63 so that lubricant splashed upon the lip 64 will run off and onto the cam 61 and roller-head 63 for continuously lubricating same, as is manifest. A rocker arm adjusting screw 65 120 has threaded connection with the lower end of the lower rocker arm 56 for adjusting the distance of play desired between the plunger 58 and screw 65.

The plunger 58 is provided with a periph- 130

eral groove 66 adapted, when the plunger 58 is in its outermost position to communicate with an oil channel 67 formed in the wall of the crank-case. This arrangement 5 permits lubricant that may flood around the plunger to find its way back into the crank-case.

10 A spark plug 68 is carried in the threaded opening 87 in the upper wall 38 of the compression block 24.

The modification shown in Fig. 5, is exactly like the other figures, excepting that the cylinder 69 is separate from the compression sleeve bearing 70, as clearly shown.

15 In this instance the cylinder 69 acts only as a dust jacket for the inner working parts, as is manifest. The cylinder 69 has no water chamber.

The operation of the motor is as follows: 20 The motor is a four cycle motor. The gas is admitted into the explosion chamber 28 and then to expansion chamber 27, through the gas inlet valve in the downward stroke of the compression-sleeve 17. The gas is 25 compressed into the explosion chamber 28 and partly within the expansion chamber 27, as is manifest, with the up-stroke of the compression-sleeve. Upon completing the compression stroke the gases are ignited by 30 means of a spark from spark plug 68 and the force of the explosion in chamber 28 forces the compressing-sleeve downwardly. The next up-stroke exhausts the burnt gases through the exhaust valve, as is manifest. 35

The lubricating system provided for in this type of motor, it will be observed, is continuous and may be termed a full splash and floating system.

40 It will be observed that lubricant will collect in the annular channels 12 and 23 from the wall of the compression sleeve during the reciprocating movements of the compression sleeve thus providing continuous lubrication for the outer surface of the compression sleeve 17 as well as for the outer surface of the compression block 24.

45 From the foregoing description, it will be observed, that the bearing surface furnished by the compression-sleeve bearing and that of the compression block eliminates possibility of what is known as piston slap, thus preventing loss of compression due to compression-sleeve and compression-block walls 50 wearing.

55 Copies of this patent may be obtained for five cents each, by addressing the "Commissioner of Patents, Washington, D. C."

It will be observed that it is impossible to flood and choke this motor with oil, because of independent upper and lower motor lubrication. Oil from the crank-case cannot in any way flood the motor. This feature 60 adds possibility of running the motor at any angle or upside down, as is manifest.

From the above it will be seen that I provide a motor which is simple in construction and operation, positively lubricated, one that can be rapidly assembled, as well as dismembered in locating trouble, and a motor which has no bearing faces liable to abuse due to unreliable lubricating 70 system.

The particular details of construction illustrated are not essential to the invention, and in view of the fact that many changes may be made without departing from the principles of the invention, I reserve the right to make any such changes or modifications as may fairly fall within the scope of the appended claim when fairly construed. 75

The many advantages of the herein described invention will readily suggest themselves to those skilled in the art to which it appertains. 80

What I claim is:

In an internal combustion engine of the class described, comprising a reciprocating piston sleeve in telescopic relation with a stationary compression block to form an expansion chamber between the stationary compression block and the piston sleeve and a water jacket surrounding the compression block and the piston sleeve, an oil space having a beveled lower end formed between the inner wall of the water jacket and the wall of the piston sleeve, a spiral oil groove formed upon the outer face of the wall of the compression block, an oil groove formed at the upper end of the piston sleeve, and a water chamber formed in the compression block having a side water inlet passage communicating at its lower end with the water chamber formed in the compression block and said water chamber having an outlet opening formed near the upper face thereof. 90 95 100 105

In testimony whereof, I have hereunto signed my name to the specification.

GEORGE L. STREBLER.
